Fritz R. Johnson, Providence, R. I.

Application August 3, 1934, Serial No. 52,803

Term of patent 14 years

To all whom it may concern:

Be it known that I, Fritz R. Johnson, a citizen of the United States, residing at Providence, county of Providence, State of Rhode Island, have invented a new, original, and ornamental Design for a Vanity Case, of which the following is a specification, reference being had to the accompanying drawing, forming part thereof.

Fig. 1 is a plan view of a vanity case showing my new design, and

Fig. 2 is an edge view thereof.

The principal and dominating features of my design reside in the enlarged overhanging hood-like upper portion of the vanity case, as viewed in side elevation, associated with the depending lower portion emerging therefrom and presenting to the whole design a configuration resembling an acorn in general outline.

I claim:

The ornamental design for a vanity case, as shown and described.

FRITZ R. JOHNSON.
